UNITED STATES PATENT OFFICE.

VERNON BRADY, OF MCKEESPORT, PENNSYLVANIA.

CURTAIN-POLE.

No. 899,288.

Specification of Letters Patent.

Patented Sept. 22, 1908.

Application filed April 7, 1908. Serial No. 425,711.

To all whom it may concern:

Be it known that I, VERNON BRADY, a citizen of the United States of America, residing at McKeesport, in the county of Allegheny and State of Pennsylvania, have invented certain new and useful Improvements in Curtain-Poles, of which the following is a specification, reference being had therein to the accompanying drawing.

10 This invention relates to a curtain fixture, and the objects of my invention are, first, to provide positive and reliable means for fastening curtains to a curtain pole; second, to obviate the necessity of using rings and pins as a fastening means; third, to provide a simple and inexpensive curtain fastener, and fourth to provide a fixture by which curtains can be easily draped upon a curtain pole.

I attain the above objects by a fixture that 20 will be presently described in detail and then specifically pointed out in the appended claims.

In the drawings forming a part of this specification, Figure 1 is a front elevation of 25 my curtain fixture. Fig. 2 is a perspective view of a portion of the same. Fig. 3 is a horizontal sectional view of a portion of the fixture, and Fig. 4 is a cross sectional view of the fixture.

30 In the accompanying drawings, 1 designates a curtain pole of a conventional form. This pole at each end is provided with a hanger 2 having a slot 3 formed therein. The hanger embraces a portion of the pole 35 and is secured thereto by a screw 4.

Adjustably and pivotally connected to each hanger are tubes 5 and 6, said tubes being fixed with relation to the hanger 2 by a set screw 7. The tubes 5 are connected together by a rod 8 provided intermediate its ends with a revoluble button 9. In the tubes 40 6 are loosely mounted rods 10 having their confronting ends provided with eyelets 11. The curtains 12 to be suspended from the

curtain pole 1 are draped over the pole and 45 caught between the tubes 5 and the tubes 6, the tubes 6 being locked in engagement with the tubes 5 by the button 9 which is rotated one-quarter a revolution after the eyelets 11 have been placed in engagement with said 50 button. The curtains can be simply draped from the tubes 5 and 6 if desired.

The slotted hangers 2 permit of the tubes 5 and 6 being adjusted vertically with relation to the pole 1, while the telescoped rods 55 8 and 10 permit of the fixture being adjusted for curtain poles of various lengths and window frames of various widths.

My fixture is constructed of light and durable metal and can be easily applied to an 60 ordinary curtain pole.

It will be noted that such changes as fall within the scope of the appended claims can be resorted to without departing from the spirit of the invention.

Having now described my invention what I claim as new, is;

1. In a curtain fixture, the combination with a curtain pole, of slotted hangers carried thereby, tubes adjustably connected to 70 said hangers, a rod for connecting some of said tubes, a revoluble button carried by said rod, rods carried by the other of said tubes and having eyelet ends adapted to engage upon said button, substantially as and for 75 the purpose described.

2. The combination of a curtain pole, of hangers carried thereby, tubes adjustably connected to said hangers, rods carried by said tubes, and means carried by one of said 80 rods for holding the other of said rods in engagement therewith.

In testimony whereof I affix my signature in the presence of two witnesses.

VERNON BRADY.
